PORTABLE COMBINATION POWER TOOL

Charles J. Rozell, Wabash, Ind.

Application October 13, 1958, Serial No. 766,957

4 Claims. (Cl. 144—1)

This invention relates to power tools and more particularly to a completely portable combination work shop.

It is an object of the present invention to provide a portable work unit having a plurality of various power tools that may be selectively used for accomplishing different results during the repair and maintenance of various types of equipment.

Another object of the present invention is to provide a portable work shop in the form of a substantially rigid main frame that is supported upon wheel and axle assembly for movement from one location to another in a simple and efficient manner.

A further object of the present invention is to provide a portable work shop of the above type having a single motive power drive means for selectively energizing any one of a number of different power tools for performing different tasks whenever required.

Other objects of the invention are to provide a portable work shop bearing the above objects in mind which is of simple construction, has a minimum number of parts, is inexpensive to manufacture and efficient in operation.

For other objects and for a better understanding of the invention, reference may be had to the following detailed description taken in conjunction with the accompanying drawing, in which:

Figure 1 is a side elevational view of a portable work shop made in accordance with the present invention with a drill press forming a part thereof in operative use;

Figure 2 is a top plan view of the apparatus shown in Figure 1;

Figure 3 is an end elevational view of the apparatus shown in Figure 1;

Figure 4 (Sheet 1) is an opposite end view similar to Figure 3;

Figure 5 is an enlarged fragmentary plan view taken along line 5—5 of Figure 4;

Figure 6 is an enlarged fragmentary cross sectional view taken along 6—6 of Figure 1; and

Figure 7 (Sheet 1) is an enlarged fragmentary cross sectional view taken along line 7—7 of Figure 3.

Referring now more in detail to the drawing, a portable work shop 10 made in accordance with the present invention is shown to include a main frame 12 that is supported upon an underframe 14 that is rollably carried by a pair of wheels 16. The opposite end of the main frame 12 includes depending support bars 18 upon which caster wheels 20 are carried for facilitating the movement of the unit from one place to another.

Mounted centrally upon the main frame 12 is an electric motor 22 having a drive shaft a pair of pulleys 24, one at each end, selectively controlled by a manually operated clutch assembly 26 for selectively driving one or the other thereof, as may be required.

The base 28 of a drill press 30 is integrally connected to a mounting plate 32, as is more clearly shown in Figures 5 and 6, which is pivotally supported by the main frame for selective movement between an operative and an inoperative storage position. A bearing plate 34

2

rotatably engages a transversely extending pivot shaft 36 that is connected at one end to one extremity of an angle bracket 38 which is pivotally supported at its opposite end to the lowermost end of a hanger pivot shaft

5 40, which pivot shaft is integrally connected to the main frame 12 beneath the level of the table top 42. A bearing post 44 also connected to the mounting plate 32 rotatably supports a pulley shaft and associated pulleys 46 around which pulley belts 50, 48 are trained for effectively transmitting power from the motor 22 to the head of the drill press, as may be required. An angle brace 52 having cutouts 54 at opposite ends serves as a main support stay for the drill press in the operative position illustrated in Figure 1. As is more clearly shown in Figures 3 and 7 of the drawing, the lower end of the brace 52 is engaged with a stud 56 on the underframe, while the opposite upper end thereof is engaged by the outermost end of the transversely extending pivot shaft 36, between the head thereof and the bearing plate 34. However, in response to removal of the brace 52, the drill press 30 may be first rotated about the transversely extending shaft 36 to a horizontal position, and then rotated as a unit about the vertical longitudinal axis of the vertical pivot shaft 40 into a storage position beneath the

10 top 42 of the unit, as shown in Figure 4.

The top 42 is hingedly carried upon the main frame 12 by means of hinge assemblies 58 for selective movement between a normally horizontal and an open angular position, such as shown in Figure 2. Raising the top 42 provides access to a circular saw assembly 60 in which the blade 66 is rotatably supported upon a shaft 64 carried by the main frame 12 and which is driven by a pulley 62 from a belt 50 that is trained about one of the drive pulleys 24 on the motor shaft. The top 42 may be raised

15 to replace or adjust the saw blade 66. In the event that it is desired to use the apparatus as a disc sander, the saw blade 66 is replaced with a circular sanding wheel, in a manner well known to those skilled in the art. When in use as a saw, the blade 66 projects upwardly through an elongated slot 68 in the top 42, as shown in Figure 2. A miter gauge assembly 70 is adjustably supported within a transversely extending guide channel 72 for use with the disc sander and saw blade, as may be required.

20 Adjacent to the motor 22, a compressor 74 is mounted and driven by a pulley belt 76 from a pulley wheel carried by the motor drive shaft. This compressor 74 is operative to compress air and store it within a compressed air storage tank 78 having an outlet valve 80 for supplying air under pressure to a spray gun 82 that may be used in various painting operations.

25 It will now be appreciated that a complete work shop is provided upon a single main frame for movement between various working locations, such work shop providing for a drill press, circular saw, sander, and source of pressurized air for spray painting purposes. A manually operated switch 84 enables the unit to be conveniently energized and deenergized, for safety purposes.

30 While various changes may be made in the detail construction, it shall be understood that such changes shall be within the spirit and scope of the present invention as defined by the appended claims.

35 What I claim as new and desire to protect by Letters Patent of the United States is:

40 1. A portable combination power tool comprising a main frame, wheels rollably supporting said main frame upon a surface, motive power means carried by said main frame, tool means carried by said main frame, power transmission means selectively drivingly connecting said motive power means to said tool means, said tool means including a drill press, a bracket pivotally supporting said drill press upon said main frame for selective movement between an upright operative position and a

collapsed storage position, said bracket comprising a mounting plate integral with said drill press, a vertical pivot shaft depending from said main frame, a transversely extending pivot shaft carried by said mounting plate, and an angle bracket pivotally connected at opposite ends to the lower end of said vertical pivot shaft and one end of said transversely extending pivot shaft.

2. The combination according to claim 1, wherein said transversely extending pivot shaft supports said mounting plate for rotation about a horizontal axis, and said vertical pivot shaft supports said mounting plate for rotation about a vertical axis.

3. The combination according to claim 2, wherein said motive power means comprises an electric motor having a drive shaft and integral drive pulley, and a manually operated clutch acting between said drive shaft and said drive pulley.

4. The combination according to claim 3, further com-

prising a brace bar selectively engageable at opposite ends with said transversely extending pivot shaft and said main frame releasably securing said mounting plate against rotation about said horizontal and vertical axes.
